(57) **CLAIM**

The ornamental design for a “football-shaped bottle opener assembly for use with a baseball cap,” as shown and described.

DESCRIPTION

FIG. 1 is a perspective view of a football-shaped bottle opener assembly for use with a baseball cap, showing my new design;

FIG. 2 is a top plan view thereof;

FIG. 3 is a bottom plan view thereof;

FIG. 4 is a left side elevational view thereof, the right side elevational view being a mirror image thereof;

FIG. 5 is a front elevational view thereof; and,

FIG. 6 is a rear elevational view thereof.

The broken line showing of a baseball cap is for illustrative purposes only and forms no part of the claimed design.
